UNITED STATES PATENT OFFICE

119,850

DESIGN FOR A TRAVELING BAG

Maurice B. Shwayder, Denver, Colo.

Application May 6, 1939, Serial No. 84,828

Term of patent 14 years

To all whom it may concern:

Be it known that I, Maurice B. Shwayder, a citizen of the United States, residing at Denver, in the county of Denver and State of Colorado, have invented a new, original, and ornamental Design for a Traveling Bag, of which the following is a specification, reference being had to the accompanying drawing, forming part thereof.

In the drawing:

Fig. 1 is a perspective view of a traveling bag illustrating the new design.

Fig. 2 is an end view thereof.

Fig. 3 is an enlarged fragmentary detail view illustrating the adjoining corners of the two parts of the bag.

I claim:

The ornamental design for a traveling bag, as shown.

MAURICE B. SHWAYDER.
